UNITED STATES PATENT OFFICE

PAUL W. LEHMAN, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS

WIND-UP APPARATUS

Application filed June 30, 1928. Serial No. 289,559.

My invention relates to machines for cutting and winding web materials and more particularly to machines for cutting and winding tacky rubber materials used in the manufacture of rubber articles such as pneumatic tires, inner tubes, etc., and has for its object to provide a machine that will be automatic in operation and have favorable stock handling conditions, thus reducing the manual labor usually involved to a minimum.

In the accompanying specification and drawings I have shown one embodiment of my invention in which,

Fig. 1 is a plan view of a cutting and winding machine;

Fig. 2 is a side elevation of the machine shown in Fig. 1;

Fig. 3 is a detail perspective view of certain working parts of the machine;

Fig. 4 is a partial side elevation but taken on the opposite side from that shown in Fig. 2;

Fig. 5 is a view taken on line 5—5 of Fig. 4;

Fig. 6 is a sectional view taken on line 25 of Fig. 5; and

Figs. 7, 8 and 9 are diagrammatic views showing the operation of the cutting and winding mechanisms.

In the drawings 10 represents a general supporting frame on which is mounted a motor 11 driving, thru reduction unit 12 and chain drive 13, a shaft 14 to which is attached a standard two-way clutch 15. One end of clutch 15 is connected by chain drive 16 to a shaft 17 on which is mounted a conveyor driving roll 18 driving a conveyor belt 19. The other end of clutch 15 is connected by chain drive 20 to a shaft 21 which is in turn connected by chain drive 22 to a shaft 23 bearing an indexing cam 24 which engages a clutch shifting member 25. A tension spring 26 is pinned to the clutch shifting member 25 and tends to hold the latter in the position shown in Fig. 1 and an operating lever 27 permits a manual operation of the clutch 15. Also connected to shaft 21 by chain drive 28 (see Fig. 4) is a cam driving shaft 29 which is in turn connected by chain drive 30 to another cam driving shaft 31.

Pivoted and supported on the shaft 17 (see

Figs. 2, 3 and 4) is a swing frame 32 which supports guiding rolls 33 driven by a belt drive 34 and complementary gears 35. Cam rollers 36 attached to the swing frame 32 engage with cams 37 on cam shaft 29 to determine the movements of the guiding rolls 33. Also pivoted and supported on shaft 17 is another swing frame 38 carrying a heated knife 39 which, as shown in Fig. 6, may be insulated as at 40 and heated by an electric unit 41. Indirectly connected to the swing frame 38 by spring arrangements 42 (Fig. 5) are cam rollers 43 engaging cams 44 on cam drive shaft 31 to determine the movements of knife 39 and thru spring arrangements 42 to produce a yieldable pressure on the knife 39 as it comes against the cutting supports 45.

Attached to shaft 17 (see Figs. 1 and 3) is another two-way clutch 46 adapted by clutch shifting member 47 on shaft 48, linkage 49, shaft 50, and linkage 51, to be shifted first one way and then the other by the movements of swing frame 32. One end of the clutch 46 drives thru chain drive 52, shaft 53, bevel gears 54, vertical shaft 55 and bevel gears 56, a winder driving roll 57 and the other end of said clutch drives thru gearing 58, shaft 59, bevel gears 60, vertical shaft 61 and bevel gears 62, another winder driving roll 63.

Positioned, as best shown in Fig. 3, beneath the winder driving rolls 57 and 63 are rolls of liner material 64 supported on trucks 65. The liners are passed over positioning bars 66 and then to windup bobbins 67 which are positioned by guideways 68 to rest on driving rolls 57 and 63 with enough pressure so that as the latter are rotated they will wind the bobbins.

The conveyor belt 19 is driven by roll 18 (see Fig. 2) while guide rolls 70, weight rolls 71 and 72 moving in guideways 73 in frame 10 and another driving roll 74 form the belt into a storage loop. The driving roll 74 is connected by chain drive 75 to a shaft 76 which is in turn driven by chain drive 77 connected to an associated manufacturing machine not shown. The shaft 76 drives a cooling roll 78 and is supported on a frame 79 which also supports another cooling roll 80.

and a guide roll 81. The chain drive 77 rotates the cooling roll 78 at a constant speed and the chain drive 75 is of such ratio that it rotates the driving roll 74 at the same surface speed as cooling roll 78.

5 The operation is as follows: a web of rubber or rubberized material is fed over the cooling rolls 80 and 78 under guide roll 81 and onto the conveyor belt 19 at driving roll

10 74. It is then carried by the conveyor belt to driving roll 18 and then down thru the guiding rolls 33 onto the liner 64 and is wound on the bobbin 67 as shown by the arrows in Figs. 1, 2, 3 and 7. As soon as the bobbin has the

15 desired amount of material the operator shifts lever 27 to reverse the clutch 15 and to simultaneously disengage the indexing cam 24. The chain drive 16, shaft 17, conveyor driving roll 18 and the windup driving roll 20 57 then become stationary and the power acting thru chain drive 20 and shaft 21 drives thru chain drive 22 and shaft 23, the indexing cam 24 and thru chain drives 28 and 30, cam driving shafts 29 and 31. Thru the action of

25 tension spring 26 the clutch shifting member 25, after one revolution of indexing cam 24, will return to the position shown in Fig. 1 to restart the conveyor driving roll 18. The ratios of the chain drives involved are such

30 that as the indexing cam 24 makes one revolution the cam shafts 29 and 31 will make one-half a revolution and the cams 37 and 44 will move the guiding rolls 33 and the cutting knife 39, respectively, as shown in Figs. 7, 8 and 9, to cut the material and position it to be wound on the opposite bobbin. As the guiding rolls 33, due to the action of cams 37, are moved from the position shown in Fig. 7 to

35 that shown in Fig. 9, the linkage 51 which is pivoted to the guide roll support 32, will act thru shaft 50 and linkage 49 to shift the clutch 46 and as the shaft 17 is restarted it will deliver the power to the gearing 58 and thru its associated gearing to its windup driving roll 63 while the windup driving roll 57 powered by the chain drive 52 will now remain stationary. At the next cutting and shifting period of operation the movements of the guide rolls 33 and knife 39 will be the

40 same but in a reversed direction, i. e., from the position shown in Fig. 9 to that shown in Fig. 7, and the power will be reshifted to winder driving roll 57 leaving winder driving roll 63 stationary.

45 As the conveyor driving roll 74 is constantly rotated it necessarily follows that when the driving roll 18 stops, the weight roll 71 will travel down and weight roll 72 will travel up in the guideway 73 thus storing the material during the cutting and shifting periods. The speed of the motor 11 may be varied by any of the several known methods, not necessary to show on the drawings, to maintain the weight rolls 72 and 73 at the proper working levels.

As will be evident from the foregoing, the machine is entirely automatic in its operation and, as there is always one windup unit stationary to permit its preparation for winding and also as the machine construction permits the use of trucks 65 to handle the liner rolls 64 and overhead tracks 82 for hoists to handle the full bobbins, it is possible for one operator to run the machine.

Having thus described my invention, I claim:

1. A device of the character described comprising a pair of web windup devices, a fixed cutting member associated with each windup device, a double edged cutting blade alternately movable into engagement with said fixed cutting members, a web guiding device adapted to guide a web of material between one of said fixed cutting members and the adjacent edge of the knife, to the associated windup device, means to move the knife to sever the web and means automatically operative upon completion of the cutting operation to move the web guiding device into position to deliver the web of material between the other fixed cutting member and the adjacent edge of the knife to the other windup device.

2. A device of the character described comprising a pair of windup devices adapted to be driven, a fixed cutting member associated with each windup device, a movable cutting member positioned to engage the said fixed cutting members, a web guiding device adapted to guide a web of material between one of the said fixed cutting members and the adjacent side of the movable cutting member to the associated windup device, means to move the movable cutting member into engagement with the fixed cutting member to sever the web of material, means automatically operative upon completion of the cutting operation to deliver the web of material between the other fixed cutting member and adjacent side of the movable cutting member to the other windup device and means automatically operative with the movement of the cutting member to alternately drive the windup devices.

3. A device of the character described comprising a pair of rotatable drums, each adapted to support and rotate bobbins to wind a substantially vertically fed sheet of material into a liner, a swinging knife positioned above the rotatable drums, a guiding device above the swinging knife positioned to guide the sheet of material and means to swing the knife and guiding device in timed relation to cut and alternately deliver the sheet of material into the liners wound on the bobbins supported by the rotatable drum.

4. A device of the character described comprising a pair of windup devices adapted to be driven to wind a substantially vertically fed sheet of material, a knife positioned above

the pair of windup devices, a guiding device positioned to guide the sheet of material to either of the windup devices, means to move the knife and guiding device in timed relation to cut and alternately deliver the sheet of material to the windup devices and means automatically operative with said movements to alternately drive the windup devices.

5. A web winding machine comprising a pair of windup devices, means to deliver a web of material into operating position with said windup devices, guiding members to guide the web of material to the windup devices, a cutting member adapted to sever the web of material, means operative to stop the delivering means and means automatically operative with said stopping means to actuate the cutting and guiding members in timed relation to sever the web of material and alternately guide the web of material to the windup devices and means operable after said movements to restart the delivering means.
